UNITED STATES PATENT OFFICE.

MORRIS T. SOUTHWICK, OF HASBROUCK HEIGHTS, NEW JERSEY, ASSIGNOR TO JOSEPH H. LYNCH, OF ASBURY PARK, NEW JERSEY.

APPARATUS FOR MARKING LAUNDRY.

Application filed November 27, 1922. Serial No. 603,595.

To all whom it may concern:

Be it known that I, MORRIS T. SOUTHWICK, a citizen of the United States, and a resident of Hasbrouck Heights, county of Bergen, and State of New Jersey, have invented certain new and useful Improvements in Apparatus for Marking Laundry, of which the following is a specification.

This invention relates to machines for affixing tags to flat articles such as the numbered tags that are used in a laundry.

The purpose of the present invention is to provide a machine that will apply tags that are characterized by not only a clasp 15 that is designed to be pressed on to the article, but also with a sliding lock that secures the clasp in its compressed form.

To this end the invention consists of certain mechanical means embodied in a machine that will perform the operations of clasping and locking the tag with the simplest possible movements on the part of the operator.

In the drawings which accompany this specification,

Figure 1 is a vertical section illustrating all the parts of the machine;

Figure 2 is a plan view of the same;

Figure 3 is an enlarged plan view of the tag holding means;

Figure 4 is an end view showing the manner of supporting the tag magazine;

Figure 5 is a section on line 5—5, Fig. 2;

Figure 6 is a horizontal section on line 6—6, Fig. 1;

Figure 7 is a view in perspective of the tag-holding plate;

Figure 8 is a view in perspective of the tag releasing jaws;

Figure 9 is a view in perspective of the tag separator and support; and

Figure 10 is a perspective view of the kind of tag that this machine is designed to handle.

The machine consists of a pedestal 1, having a table extension 2 and a top guide 3. In the center of the pedestal is a plunger 4, capable of vertical reciprocation, the same being operated downwardly through connecting rod 5 by foot-lever 6, and upwardly by spring 7 working against cross-head 8 at the top of the plunger. At 9 is shown a tag magazine (see Fig. 6) which is formed like an open-sided box with side ribs 10 and feet 11. This magazine is supported

on the table by guides 12 on which it may be slid into position to bring the tags piled therein in proper alignment under the tag applying mechanism. The tags are assembled in this magazine by being slid down over a vertical rod 13, there being a slot in the tags as shown in Fig. 10 for this purpose. A rod 14, depending from the table, has a sliding pusher 15 provided with a handle 16 and a spring 17. When a magazine of tags is introduced into its proper place the pusher 15 is depressed by the operator by means of handle 16 until the pin 18 sliding in slot 19, engages in the bayonet lock 20 on the rod 14. After the magazine is in place the operator releases the pusher from the lock, allows it to rise up against the bottom of the pile of tags and push them upward towards the table. When the tags are so pushed up, the top tag rests with the back end away from the operator against a plate 21, Fig. 3, while the two corners of the front end press upwardly against the jaws 22, which are connected together by a yoke 23 (see Fig. 8). As it is necessary to have a support or abutment under the tag that is to be affixed, I provide a sliding plate 24 (see Fig. 9) which is connected by pivotal hinge 25 with a reciprocating rod 26 (see Figs. 1 and 2), which rod in turn is pivotally connected to a bell crank 27, fulcrumed at 28. A spring 29, attached to the lower arm of the bell crank at one end and to the pedestal at the other end operates to tend to keep the sliding support normally in its forward position underneath the top tag. A handle shown in Fig. 2 at 30 enables the operator, however, to retract this sliding support whereupon the pile of tags are pushed by the spring 17 against the holding plates 21 and 22, so that upon the operator releasing the handle 30, the sliding support will be pushed by spring 29 in under the top tag, thus separating it from the rest of the tags in the magazine. After the top tag is so brought into position for use, the rest of the tags are automatically separated and supported for affixing by means of a pawl 31, pivoted at 32, in a slot in the vertical plunger. This pawl, upon the downward movement of the plunger by the pedal, engages under the bell crank 27, so that when the plunger is lifted by the action of the spring 7 it retracts the sliding support 24 through the medium of the bell 105 110

crank 27 and the connecting rod 26. Before the plunger reaches the upper end of its stroke, however, the heel 33 of the pawl impinges upon the lower end of a stop bolt 34, which forces the pawl to trip the bell crank, whereupon the spring 29 causes the sliding support to again insert itself under the top tag in the magazine.

I will now describe the mechanism for closing and locking the tag. The tag, as will be shown by an inspection of Fig. 10, consists of a clasp, with an upper and a lower wing, the latter having a slot for guiding the same on the pin of the tag magazine, and the former having projections indicated at 35, which match up with recesses in the lower wing so that when the two wings are pressed together they will secure any flat article placed between them. To hold the two wings in the closed together position, a lock or bolt 36 is secured slidably on the upper wing, and flanges 37 on the lock, may be made to engage under lips 38 on the lower member to hold the clasp in its closed position.

The tag affixing member 39 (see Figs. 1 and 2) has a corrugated hammer-end at 40 immediately over the pile of tags in the magazine and is pivoted at 41 to the frame 30 of the machine on bracket 42. A lost motion is provided to allow of a limited longitudinal play of the member 39, and a set screw 43 may be used to adjust the backward movement of the member. The backward movement is accomplished by a spring 44, attached to pin 45 on the member at one end and to pin 46 on the fixed bracket 42 at the other end. The forward end of the member is, therefore, capable of both a longitudinal back and forward movement, and an up and down movement. Its upward movement may be limited by a set screw 47 in bracket 48 on the frame of the machine.

To close the clasp and slide the lock into place requires both a downward pressure and a forward pressure and the means I have shown in the present machine to accomplish this are as follows:—

On the plunger I attach a cam 49, having two inclined surfaces on its forward end, and on the affixing member I mount a roller 50 against which the cam 49 will impinge when the plunger 4 is brought down by pedal 6. The first effect of this impingement will be to depress the affixing member 39 until the hammer-end 40 impinges upon the tag to close the same. A further downward movement, however, causes the cam to push the roller forward and the affixing member, being then in contact with the lock on top of the tag, pushes it also forward and slides it into its locked position with the flanges 37 under the lips 38. Corrugations on the top of the lock make this sliding of the lock by the hammer-head more certain.

As the affixing member moves forward, a lip 51, attached thereto, impinges against a bracket 52, mounted on a yoke 23 (see Figs. 1 and 8). This causes the yoke 23 with its retaining jaws 22 to move forward far enough to uncover the forward ends of the tag, when the article, together with its attached tag may be removed from the machine, as soon as the affixing member is raised, which is accomplished by the spring 44 retracting the same immediately, upon the operator releasing pressure from the pedal. At 53 I have shown a counter which will register the number of pieces operated upon.

To operate the machine a piece to be tagged is slipped in between the upper and lower wings of the top tag until it comes against upright projections 54 (see Figs. 1, 3, and 7). The pedal being then depressed, the affixing member 39 is pushed down by the cam 49 acting on the roller 50, on to the locking plate 36, and presses the two wings of the clasp together. A further movement of the lever causes the cam 49 to push the roller 50 forward and the corrugated hammer-end 40 being then in close contact with the sliding lock on top of the tag causes the same to be slid into its locking position with the flanges 37 pushed under and held down by the lips 38. Releasing the pressure from the foot-lever, the operator may then remove the article with the tag attached and locked thereon and automatically the machine, through the instrumentality of the pawl 31, bell crank 27, rod 26 and support 24 as already described, brings a second tag into position, whereupon the operations may be repeated until all the articles requiring the same identification number have been tagged. The magazine 9 may then be removed from the machine and another magazine with a pile of tags having a different identification number put in its place.

I claim:—

1. In a machine for affixing tags which have a clasp and sliding lock the combination of means for holding the tag with means for closing the clasp and sliding the lock.

2. In a machine of the character described, a tag affixing member, means for moving the tag affixing member both downwardly onto the tag and longitudinally along the tag.

3. In a machine of the character described, means for holding a tag, a tag affixing means, means for moving the tag affixing means both downwardly onto the tag and longitudinally along the tag.

4. In a machine of the character described, means for holding a tag, a tag affixing means, means for moving the tag affixing means both downwardly onto the tag to close the same and longitudinally along the tag to lock the same in its closed position.

5. In a machine of the character described,

means for holding a tag, a tag affixing means, means for moving the tag affixing means both downwardly onto the tag and longitudinally along the tag, and means for 5 retracting said tag affixing means.

6. In a machine of the character described, a tag magazine and a tag retaining means, a tag affixing means, means for moving the tag affixing means both downwardly onto 10 the tag and longitudinally along the tag and means for releasing the tag retaining means.

7. In a machine of the character described, a tag magazine and a tag retaining means, a tag affixing means, means for moving the 15 tag affixing means both downwardly on to the tag and longitudinally along the tag and means for releasing the tag retaining means operated after the tag affixing means impinges on the tag.

20 8. In a machine of the character described, a tag magazine adapted to hold a pile of tags, a tag affixing means, means for moving the tag affixing means both downwardly on to the tag and longitudinally along the tag 25 and a sliding tag support insertable under the top tag and means for inserting and withdrawing said support.

9. In a machine of the character described, a tag magazine adapted to hold a pile of 30 tags, a tag affixing means, means for moving the tag affixing means first downwardly on to the tag and then longitudinally along the tag, means for retracting the tag affixing

means, a tag support, means for inserting the tag support under the top tag of the pile 35 before the tag affixing means is applied to the tag, and means for withdrawing the tag support after the tag affixing means has been applied to the tag.

10. In a machine of the character described, a tag magazine adapted to hold a pile of tags, a tag affixing means, means for moving the tag affixing means first downwardly on to the tag and then longitudinally 40 along the tag, means for retracting the tag 45 affixing means, a tag support, means for inserting the tag support under the top tag of the pile before the tag affixing means is applied to the tag, means tending to withdraw the support, restraining means for said withdrawing means and means for tripping said restraining means.

11. In a machine for affixing tags, the combination of a tag affixing means, a tag 55 magazine adapted to receive a pile of tags and removably supported on the machine, means for pushing the pile of tags toward the tag affixing means, a tag retaining means limiting the movement of the tags toward the affixing means, a tag support, means for 60 inserting the tag support under the top tag before the tag affixing means is applied to the tag and means for withdrawing the support after the tag affixing means has been applied to the tag.

MORRIS T. SOUTHWICK.
